UNITED STATES PATENT OFFICE.

NINA F. WOLLAM AND HOWARD WOLLAM, OF PULLMAN, NEBRASKA, ASSIGNEES OF ONE-HALF TO GRACE WOLLAM AND MORRIS WOLLAM, BOTH OF HAGIE, WYOMING.

BABY-JUMPER AND GOCART.

1,370,176.

Specification of Letters Patent.

Patented Mar. 1, 1921.

Application filed April 10, 1919. Serial No. 288,983.

To all whom it may concern:

Be it known that we, NINA F. WOLLAM and HOWARD WOLLAM, citizens of the United States, residing at Pullman, in the county 5 of Cherry and State of Nebraska, have invented certain new and useful Improvements in Baby-Jumpers and Gocarts, of which the following is a specification.

This invention relates to a combination 10 baby jumper and gocart, the primary object being to provide an improved structure adapted to be used as a swing, gocart, high-chair, or crib.

The invention contemplates the provision 15 of a removable seat or chair adapted to be mounted upon a carriage frame so that the device may be readily used as a carriage, to be pushed from place to place, but which may be readily converted into a resiliently 20 suspended swing or jumper in which the child may sit without danger of falling from the chair.

A further object of the invention is the provision of a device of this character which 25 consists of comparatively few parts and is simple in construction but durable and well adapted to withstand the rough usage to which devices of this character are ordinarily subjected.

30 For a full description of the invention and the advantages and merits thereof reference is to be had to the following description and accompanying drawings, in which:—

35 Figure 1 is a side elevation of the device constructed in accordance with our invention.

Fig. 2 is a plan view of the same.

Fig. 3 is a fragmentary front elevation.

40 Fig. 4 is a detail elevation, partly in section, showing a portion of the structure comprising the invention.

Fig. 5 is a detail view of a part of the invention.

45 Fig. 6 is a fragmentary section taken through the food tray.

Referring to the drawings wherein is illustrated the preferred form of our invention, in which like characters of reference indicate like or corresponding parts throughout the several views, a portable frame 1 is provided which includes the four

upright legs 2, the lower ends of which are provided with the wheels 3 which will permit the same to be readily wheeled from 55 place to place. A container 4 is attached to the upper ends of the legs 2 and comprises a box for receiving the infant's wearing apparel and makes a convenient compartment for any articles of clothing worn by the 60 child. The container 4 may be of any desired depth and the front wall of the container is provided with a hingedly mounted door 5 through which access may be gained to the compartment. 65

Mounted upon the top of the box 4 is the seat 6 the center of which is provided with a suitable opening 7 whereby the seat may serve as a stool for the child; the compartment 4 being adapted to receive a suitable 70 vessel when the chair is used for this purpose. The seat 6 has a supplementary cover panel 8 the side edges of which are provided with tongues to be received in parallel grooves provided in the side edges 75 of the recess 9 which receives the panel 8 thereby permitting the panel to be slid inwardly or outwardly to cover or uncover the opening 7.

The back of the chair indicated at 10, 80 comprises the upright members 11 having the back pieces 12 connected thereto the lower ends of the upright members 11 being hingedly connected as at 13 to the seat. This permits the back to be swung down- 85

wardly to serve as a back rest for the child when it is sleeping. The back is held in an upright position to serve as a support for the child's back when the child is sitting upright, by the side arms 14, the ends of 90 which are provided with loops 15 as shown in Fig. 5 of the drawing, these loops being adapted to be engaged by the hooks 16 pivotally mounted on the uprights 11. The hooks, therefore, may be disengaged from 95 the eyelets 15 so that the back may be swung on its hinges to the desired position. The side arms also include the front upright members 17 which have the arm portion rigidly connected thereto. The uprights 11 and the uprights 17 have their upper ends provided with eye loops 18 each of which is adapted to receive a snap hook 19 connected to a suspension strap 20. 100

The four suspension straps 20 are adapted to suspend the seat when the portable frame has been removed from beneath the chair and the side braces 21 arranged in parallelism, have their ends connected to two of the straps as indicated at Fig. 1 of the drawing and suspension springs 22 are connected as shown and have their upper ends joined together and fixed to a supporting eye loop 23 fastened to the ceiling whereby the chair may be resiliently suspended.

A food tray 24 is provided and the same consists of a substantially rectangular plate having laterally extending portions 25 which rest upon the side arms 4. The central portion of the plate is provided with a depression 26 shown to advantage in Fig. 6 and in this depression is fitted a suitable food container such as a porcelain plate 27 serving as a vessel to receive the child's food. This food tray is supported by the supporting bar 28 which has its upper end provided with a right angularly extending tongue 29 adapted to be extended through a sleeve 30 fixed to the bottom of the food tray. The opposite end of the supporting bar 28 is provided with a similar right angular extension 31, the end of which is received in a slot 32. The slot 32 is provided in a board 33 which is hingedly connected to the front edge of the seat and is adapted to serve as an extension for the seat to form the bottom for the crib or couch when the device is used in this capacity as will be indicated by dotted lines in Fig. 1. The lower edge of the board 33 has a foot rest 34 and this is provided with eyelets 35 to which may be attached suitable fastening straps 36 adapted to be connected to the eyelets 37 on the inner side of the uprights 17 so that the extension board 33 may be held in position.

A canopy 38 is provided for use when the device is used as a gocart and this canopy comprises the frame bars 39 which have their meeting ends adapted to be connected to pintles 40 carried by the side arms of the seat so that the canopy may be swung backwardly in the manner similar to devices of this character when the apparatus is in use as a gocart. A suitable handle bar 41 is also attached and extends from the rear of the structure to serve as a convenient hand-grip for pushing the gocart when in use.

It will be noted that the above structure provides an almost universal combination of structures especially arranged for the convenience and comfort of the child during all hours of the day and night.

The foregoing description and accompanying drawings have reference to what might be considered to be the preferred or approved form of our invention. We desire it to be understood that we may make such changes in the construction, combination and

arrangement of parts, materials dimensions, et cetera, as may prove expedient and fall within the scope of the appended claims.

Having thus fully described our invention what we claim as new and desire to secure by Letters Patent, is:—

1. A convertible chair, a seat, a back, pivotally mounted to said seat, means for limiting the movement of said back when it is moved downward into a substantial coplanar relation with said seat, a foot rest depending from the foot of said seat, hinged to said front, means for limiting the upward movement of said foot rest to a position substantially coplanar to the bottom of said seat and back and for retaining said foot rest in said coplanar position, a vertically upstanding member on each side of the front of said seat and carrying backwardly extending sides to said seat, a vertically upstanding member upon each side of said back, said vertically upstanding members provided with means for attaching them in suspended relation thereabove, whereby said chair may be converted into a swing, a bed, or a chair.

2. In a chair, a pair of side members having a horizontal upper face, with upstanding lugs at the front thereof, a tray adapted to fit between said lugs, and provided with laterally extending lugs adapted to slide upon said sides and engage said upstanding lugs in forward motion, a bracket provided with a rearwardly extending projection underneath said tray and a channel in said tray to slidably receive said projection, whereby the said tray may be moved rearwardly until it engages the occupant, and will have a limited forward movement.

3. A convertible chair structure comprising polygonal vertical corner posts, longitudinal braces therefor forming the sides of a box at the top thereof, a combined shelf and brace extending between said longitudinal braces, a back to said box functioning also as a brace between said longitudinal braces, a hinged door at the front of said box, a seat mounted on the top of said standards provided with a sliding cover for said box, and a perforation in said seat covered by said sliding cover, a depending board hingedly mounted at the front of said seat and concealing said door when in a downward position, a depending member provided at its distal end with a foot rest.

4. A convertible chair structure comprising polygonal vertical corner posts, longitudinal braces therefor forming the sides of a box at the top thereof, a combined shelf and brace extending between said longitudinal braces, a back to said box functioning also as a brace between said longitudinal braces, a hinged door at the front of said box, a seat mounted on the top of said standards provided with a sliding cover for said

box, and a perforation in said seat covered by said sliding cover, a depending board hingedly mounted at the front of said seat and concealing said door when in a downward position, a depending member provided at its distal end with a foot rest, said foot rest provided with an eye, vertically upstanding posts upon said seat at the front thereof on each side, a longitudinally extending arm rest mounted to said upstanding posts extending rearwardly over the back of said seat and provided with a catch, a pair of back supports pivotally mounted to the back of said seat, a mount for a canopy frame affixed to the side of said arm rest,

said pivotally mounted back support provided with means for engagement with said catch when in a vertical position, and means mounted upon the upwardly extending posts for engagement with the eye in said foot rest 20 when the same is in elevated position.

In testimony whereof we affix our signatures in presence of two witnesses.

NINA F. WOLLAM.
